UNITED STATES PATENT OFFICE.

JOHN WILFRED HAUGHTON, OF CULLYBACKEY, NORTHERN IRELAND.

BEETLING ENGINE.

Application filed December 22, 1927, Serial No. 241,827, and in Great Britain May 16, 1927.

This invention relates to the beetling of cloth and has for its object to provide an improved beetling engine.

According to the invention, I provide a beetling engine in which the fallers or beetles are arranged between cloth rollers and are associated with means whereby they can be made to operate by gravity on the said rollers for the purpose of beetling the cloth. Preferably, the fallers or beetles are pivotally mounted and so arranged and oscillated that they operate at each end of their oscillating movement to effect the beetling of the cloth carried round the rollers. The pivotal fallers or beetles may be adapted for oscillation between a pair of cloth rollers and the arrangement may be such that each of the beetles, in the upward part of its oscillation, is positively operated and completes its further movement under gravity, free of control other than by the pivot, so that the equivalent of the dropping action of the usual vertically moving beetles is obtained.

Preferably, means is provided for rendering one or more of the beetles inoperative in respect of either the whole or the half of the beetling operations thereof, and means are also provided whereby the beams being treated are rotated and traversed in any usual manner, for the purpose of obtaining an even beetling of the cloth.

One form of beetling engine embodying my invention will now be described, by way of example, with reference to the annexed drawings, in which:

Fig. 1 is a side elevation of the beetling engine;

Fig. 2 is a front elevation; and

Fig. 3 is a plan view.

Referring to the drawings:

The beetles 1, of substantially T shape in end elevation, are pivotally mounted on a shaft 2. This shaft is supported in bearings 3 on a frame 3, at each side of which a pair of plummer blocks 4 is carried. In these plummer blocks, the shafts 5 and 6 of rollers 7 and 8 are mounted respectively.

As will be seen from Fig. 1, the T-shaped beetles 1 extend a short distance below their pivotal shaft 2, being each provided with a lower extension 9 bolted to the upper portion of the beetles so as to complete the bearing 10 thereof. At the bottom of the extension 9, a roller 11 is rotatably mounted.

In the lower portion of the frame 3, jour-

nals 3^a are provided for a series of slideable guide rods 12, the said rods being horizontally disposed at equal distances from one another. On each rod 12, a pair of spaced 60 flank-members 13 and 14 are fixed by cotters 16 and gibs 17, the said members 13, 14 being connected together at their lower ends by a rigid bar 15, which is fixed to the flank-members 13, 14 by cotters 16^a and gibs 17^a. 65 A shaft 18 extends horizontally through the whole of the flank-members 13 and 14, and cams 19, working, if desired, in an oil bath, are keyed to the shaft 18 so that one such cam is located directly between each pair of 70 flank-members 13, 14. As will be seen from Figs. 1 and 2, each flank-member is formed on its inner face with a vertical recess 20, in which recesses are adapted to operate the respective roller 11 and cam 19. 75

Referring to Figs. 2 and 3, it will be seen that the cam shaft 18 is adapted to be connected to the power source (not shown) and is journaled at the bottom of the frame 3 in bearings 21 (Fig. 2). A worm 22 is secured to the shaft 18 so as to engage with a worm-wheel 23 fixed to the bottom of a vertical shaft 24, the top of which carries a bevel gear 25. As shown in Fig. 1, the bevel gear 25 meshes with a bevel gear 26 secured 80 to a horizontal shaft 27, which latter also carries a pair of bevel gears 28, 29 meshing respectively with bevel gears 30 and 31. Referring to Fig. 3, it will be seen that bevel gears 30, 31 are fixed on the end of 85 shafts 32 and 33 respectively and, as shown in Fig. 2, each of the shafts 32, 33 has also mounted thereon a cam member 34 (Fig. 2). The said member 34 is formed integral with a ring of gear teeth 35, flanged at one side 90 by a bevelled collar 36 and at the other side by the bevelled face 37 of the cam member itself. The circumferential surface of the cam member 34 is formed with a cam slot 38, which, as clearly visible from Fig. 2, is 95 engaged by a fixed pin 39. The cam member 34 is slideable along, but rotatable with, the shaft 32, so that as the latter rotates, the cam member will revolve and oscillate simultaneously. The ring of gear teeth 35 on the cam member 34 is engaged by a large gear wheel 40 fixed on the shaft 5 carrying the roller 7. The said shaft 5 is slideable in its plummer block 4, the roller 7 being thereby movable to and fro as well as rotatable 100 by the gear wheels 40 engaging the geared ring 35 of the cam member. 105

As will be understood, the foregoing arrangement is duplicated at the other side of the beetling engine, so as to impart a similar rotative and oscillating motion to the roller 8. Similar traversing gear could also be used to operate a plurality of beetling engines by extending the shaft 27.

Referring again to Fig. 1, it will be seen that the rotation of the cams 19 causes the pair of flank-members 13, 14 to move from side to side on their guide rods 12. The said flank-members, being connected rigidly together at the bottom by bars 15, oscillate in unison and, by acting on the roller 11, operate to cause oscillation of the beetle 1, the said oscillation being effected during the first half thereof by the positive thrust of one or other of the flank-members 13, 14 on the roller 11, and the latter half of the said oscillation being effected simply by gravity. The beetle 1, rollers 7, 8 and flank-members 13, 14 are so arranged that the fall of the beetle 1 under gravity corresponds to a free arcuate motion of the roller 11 across from the flank-member 13 to the member 14. As will be understood, the rods 12 may be extended where a plurality of beetling engines are arranged in adjacency, so that, from one driving or operating gear, the said rods 12 may operate the plurality of beetling engines.

In order that any of the beetles 1 may be rendered inoperative with respect to either or both of the rollers 7, 8, a locking device comprising locking bars 41, (see Fig. 3) is provided. As will be seen from Fig. 2, the bar 41 for each beetle comprises a pair of spaced segmental portions, of which the axes are eccentrically disposed on opposite sides of the axis about which the complete bar 41 is rotatable. The flat surfaces 46 of the said segmental portions face outwards from each other, and are not parallel but are inclined so that they converge upwards towards each other. The segmental portions are joined by a short integral portion of circular section, and the bars 41 as a whole are each formed at the ends with a squared portion 44 (see Fig. 3) adapted to receive a key. The beetles 1 are each formed with a rectangular eye 45 above the pivotal shaft 2, and, when the locking bars 41 are turned so that the flat surfaces 46 of the segmental portions are at the same upward inclination, the said eye 45 is adapted to slide back and forward on the bars 41 as the beetle 1 is oscillated by its cam. By means of a key as aforesaid, however, the locking bars 41 can be given a partial rotation. Such rotation of the bar 41 brings the flattened surface 46 of one segmental portion into a vertical position, and brings the corresponding surface of the other segmental portion into a position nearer the horizontal, whereby, due to the lower corner of the latter seg-

mental portion projecting into the path of the rectangular eye 45, pivotal movement of the beetle 1 in the direction of the said portion is prevented. In Fig. 2, each of the bars 41 is turned so that one segmental portion thereof has its flattened surface 46 vertical and the other segmental portion is omitted so as to avoid obscuring the illustration. As will be understood, of course, the oscillation of the flank members 13, 14 continues uninterruptedly during any of the foregoing changes in the movement of the beetle.

The modus operandi of the beetling engine is as follows:—

Cloth is adapted to be wound on each of the rollers 7 and 8. As hereinbefore explained, both rollers 7 and 8 have a rotative and oscillating movement imparted to them, and, at the same time, the beetles 1 are normally adapted to be operated so that the T-shaped heads thereof fall on to the cloth rollers 7 and 8 alternately. By oscillating the rollers 7 and 8, it is ensured that the T-shaped heads of the beetles 1 act upon different parts of the cloth each time they drop downward under gravity, so that the entire area of the cloth on each roller 7 or 8 is beetled. As will be clear, the action of the beetles 1 is thus equivalent in every respect to the action of the ordinary beetles moved up and down vertically.

Furthermore, as hereinbefore described, only one, instead of both, of the cloth rollers 7, 8 may be used when desired, the beetles 1 being rendered inoperative in respect of the unused roller 7 or 8 by the locking bars 41. Likewise, it will be clear that by means of the said locking bars 41, any desired number of the beetles 1 may be rendered wholly or partially inoperative.

Preferably, the cams 19 for the beetles 1 are arranged in angular progression on the shaft 18 so that the beetles 1 will operate in similar progression on the cloth rollers 7, 8. By this arrangement, the rollers and the plummer blocks 4 thereof are relieved of severe shock, such as would occur were the beetles 1 to drop on to either roller 7 or 8 simultaneously. On the outside (Fig. 1) of the plummer blocks 4, strong channel bars 47 are secured to withstand the thrust due to the gravity action of the beetles 1 on the rollers 7, 8.

As will be seen from the drawings, the bearings 48 of the plummer blocks 4 are of the open type so that the cloth rollers 7, 8 can be readily lifted out therefrom and placed back again. In this arrangement, overhead runway or other means can be used to move the cloth rollers 7, 8 out of the house where the actual beetling takes place, so that the cloth can be put on or taken off the rollers under better conditions than usually obtain in a beetling house, where the noise

is very detrimental to good work being done. Under such conditions, also, the beetling engines can be placed closer together, thus effecting a saving of room.

5 As will also be seen from the drawings, the beetle operating mechanism is located entirely below the level of the cloth rollers, so that the said mechanism can be freely oiled without danger of the oil coming into 10 contact with the cloth. In practice, this advantage is further secured, inasmuch as the beetle operating mechanism is generally arranged below the floor level.

It will be clear that by making the same 15 beetles operate on two cloth rollers instead of one roller as usual, the output of the beetling engine is greatly increased, or, for an equivalent output, the number of beetles required is reduced, because one beetle is 20 equivalent to two beetles in the ordinary vertical machine.

Various modifications may be made in the invention without departing from the scope thereof. For example, the force of impact 25 of the beetles may be varied by varying the weight of the T-shaped or other heads thereof, which may be done by forming the said heads with recesses adapted to be partially or wholly filled with lead or other metal. 30 Such means may also be used to obtain uniformity in impact of the various beetles. It is to be observed, further, that a beetling engine as herein set forth can be made entirely of metal, thereby eliminating the 35 costly woodwork of the present beetling engines.

I claim:—

1. Beetling engines for beetling cloth comprising rollers for supporting the cloth, 40 means for rotating said rollers, pivotal supporting means, beetles pivotally mounted on the said supporting means, spaced flank members for each beetle, guide means carrying said flank members, means for slidably supporting said guide means transversely of the beetles, means for reciprocating said flank members, and means whereby the flank members are rigidly connected on their respective guide means at a 45 fixed distance apart so that the oscillation of the beetle is effected firstly by a positive thrust and then by gravity.

2. Beetling engines for beetling cloth comprising a pair of rollers for supporting 55 the cloth, means for rotating said rollers, pivotal supporting means, beetles pivotally mounted on the said supporting means, a pair of flank members for each beetle, a guide rod for carrying each pair of flank 60 members, means whereby the flank members are rigidly secured on their respective guide rods at a fixed distance apart, means for slidably supporting the guide rods transversely of the beetles, cams arranged 65 to operate on the flank members, means to

rotate said cams, and a roller on the lower end of each beetle acted on by the respective flank members so that the oscillation of the beetle is effected during the first half thereof by a positive thrust and in the latter half 70 by gravity.

3. Beetling engines for beetling cloth comprising rollers for supporting the cloth, means for rotating said rollers, pivotal supporting means, beetles pivotally mounted on the said supporting means, spaced flank members for each beetle, guide means carrying said flank members, means for slidably supporting said guide means transversely of the beetles, operating means common to said beetles for reciprocating said flank members, means whereby the flank members are rigidly connected on their respective guide means at a fixed distance apart so that the oscillation of the beetle is 85 effected firstly by a positive thrust and then by gravity, and means for rendering a number of the beetles inoperative in respect of either the whole or part of the beetling operations thereof without disturbing the 90 mounting of said beetles and the connection of the flank members to said operating means.

4. Beetling engines for beetling cloth comprising a pair of rollers for supporting 95 the cloth, means for rotating said rollers, pivotal supporting means, beetles mounted on the said supporting means, a pair of flank members for each beetle, a guide rod for carrying each pair of flank members, means whereby the flank members are rigidly secured on their respective guide rods at a fixed distance apart, means for slidably supporting the guide rods transversely of the beetles, cams arranged to operate on the flank members, means to rotate said cams, a roller on the lower end of each beetle acted on by the respective flank members so that the oscillation of the beetle is 100 effected during the first half thereof by a positive thrust and in the latter half by gravity, and means for rendering any number of the beetles inoperative in respect of either the whole or part of the beetling operations thereof.

5. Beetling engines for beetling cloth comprising a pair of rollers for supporting the cloth, pivotal supporting means, beetles pivotally mounted on the said supporting means, a pair of flank members for each beetle, a guide rod for carrying each pair of flank members, means whereby the flank members are rigidly secured on their respective guide rods at a fixed distance apart, means for slidably supporting the guide rods 115 transversely of the beetles, cams arranged to operate on the flank members, means to rotate said cams, a roller on the lower end of each beetle acted on by the respective flank members so that the oscillation 120 of the beetle is effected during the first half thereof by a positive thrust and in the latter half by gravity, and means for rendering any number of the beetles inoperative in respect of either the whole or part of the beetling operations thereof.

tion of the beetle is effected during the first half thereof by a positive thrust and in the latter half by gravity, and means whereby the cloth rollers are rotated and moved from side to side to obtain uniform beetling of the cloth.

6. Beetling engines for beetling cloth comprising a pair of rollers for supporting the cloth, pivotal supporting means, beetles 10 pivotally mounted on the said supporting means, a pair of flank members for each beetle, a guide rod for carrying each pair of flank members, means whereby the flank members are rigidly secured on their respective guide rods at a fixed distance apart, means for slidably supporting the guide rods transversely of the beetles, cams arranged to operate on the flank members, means to rotate said cams, a roller on the lower end of each beetle acted on by the respective flank members so that the oscillation of the beetle is effected during the first half thereof by a positive thrust and in the latter half by 75 gravity, an eye provided on each beetle, a locking bar passing through said eye, means for holding said locking bars against axial movement whilst permitting rotation thereof, and means whereby said bars are turnable 80 independently so as to permit and prevent sliding movement thereon of the eye engaged thereby.

7. Beetling engines for beetling cloth, comprising a pair of rollers for supporting the cloth, pivotal supporting means, beetles pivotally mounted on the said supporting means, a pair of flank members for each beetle, a guide rod for carrying each pair of flank members, means whereby the flank 90 members are rigidly secured on their respective guide rods at a fixed distance apart, means for slidably supporting the guide rods transversely of the beetles, cams arranged to operate on the flank members, means to rotate said cams, a roller on the lower end of each beetle acted on by the respective flank members so that the oscillation of the beetle is effected during the first half thereof by a positive thrust and in the latter half by 95 gravity, an eye provided on each beetle, a locking bar passing through said eye, means for holding said locking bars against axial movement whilst permitting rotation thereof, and means whereby said bars are turnable 100 independently so as to permit and prevent sliding movement thereon of the eye engaged thereby.

8. Beetling engines for beetling cloth comprising a pair of rollers for supporting the cloth, means for rotating said rollers, pivotal supporting means arranged between the said rollers, beetles adapted for oscillation 10 on the said supporting means, stopper members for said beetles and spaced flank members for each beetle, guide means carrying said flank members, means for slidably supporting said guide means transversely of the beetles, operating means common to said beetles for reciprocating said flank members, means whereby the flank members are rigidly connected on their respective means at a fixed distance apart so that the oscillation 15 of the beetle is effected firstly by a positive thrust and then by gravity, for introducing said members to stop the action of any beetle without interfering with the continued action of the beetles remaining or to stop the 20 action of a beetle on one cloth roller only while permitting action of the beetle on the other roller.

9. Beetling engines for beetling cloth comprising a pair of rollers for supporting the cloth, means for rotating said rollers, pivotal supporting means, beetles pivotally mounted on the said supporting means, a pair of flank members for each beetle, a guide rod for carrying each pair of flank members, means whereby the flank members 25

are rigidly secured on their respective guide rods at a fixed distance apart, means for slidably supporting the guide rods transversely of the beetles, cams arranged to operate on the flank members, means to rotate 70 said cams, a roller on the lower end of each beetle acted on by the respective flank members so that the oscillation of the beetle is effected during the first half thereof by a positive thrust and in the latter half by 75 gravity, an eye provided on each beetle, a locking bar passing through said eye, means for holding said locking bars against axial movement whilst permitting rotation thereof, and means whereby said bars are turnable 80 independently so as to permit and prevent sliding movement thereon of the eye engaged thereby.

10. Beetling engines for beetling cloth, comprising a pair of rollers for supporting the cloth, pivotal supporting means, beetles pivotally mounted on the said supporting means, a pair of flank members for each beetle, a guide rod for carrying each pair of flank members, means whereby the flank 90 members are rigidly secured on their respective guide rods at a fixed distance apart, means for slidably supporting the guide rods transversely of the beetles, cams arranged to operate on the flank members, means to rotate said cams, a roller on the lower end of each beetle acted on by the respective flank members so that the oscillation of the beetle is effected during the first half thereof by a positive thrust and in the latter half by 95 gravity, an eye provided on each beetle, a locking bar passing through said eye, means for holding said locking bars against axial movement whilst permitting rotation thereof, and means whereby said bars are turnable 100 independently so as to permit and prevent sliding movement thereon of the eye engaged thereby.

11. Beetling engines for beetling cloth comprising a pair of rollers for supporting the cloth, means for rotating said rollers, pivotal supporting means, beetles pivotally mounted on the said supporting means, a pair of flank members for each beetle, a guide rod for carrying each pair of flank members, means whereby the flank members are rigidly secured on their respective guide rods at a fixed distance apart, means for slidably supporting the guide rods transversely of the beetles, cams arranged to operate on the 110 flank members, means to rotate said cams, a roller on the lower end of each beetle acted on by the respective flank members so that the oscillation of the beetle is effected during the first half thereof by a positive thrust and in the latter half by 115 gravity, a rotatable shaft, means for driving said shaft, a cam member slideable on said shaft and provided with a cam slot, a fixed pin engaging with said cam slot, a geared ring rotatable and 120 slideable with said cam member, a second geared ring fixed on the shaft of each of the cloth rollers, and each rotatable and axially movable by the first mentioned geared ring to effect rotation and side to 130

side movement of the cloth rollers, stopper members for said beetles, and means for introducing said members to stop the action of any beetle without interfering with the continued action of the beetles remaining or to stop the action of a beetle on one cloth roller only while permitting action of the beetle on the other roller.

11. Beetling engines for beetling cloth comprising a pair of rollers for supporting the cloth, means for rotating said rollers, pivotal supporting means, beetles pivotally mounted on the said supporting means, a pair of flank members for each beetle, a guide rod for carrying each pair of flank members, means whereby the flank members are rigidly secured on their respective guide rods at a fixed distance apart, means for slidably supporting the guide rods transversely of the beetles, cams arranged to operate on the flank members, means to rotate said cams, a roller on the lower end of each beetle acted on by the respective flank members so that the oscillation of the beetle is effected during the first half thereof by a positive thrust and in the latter half by gravity, and reinforcement members adapted to take the thrust on the cloth rollers due to the impacts of the beetles.
12. Beetling engines for beetling cloth comprising a pair of rollers for supporting the cloth, means for rotating the said rollers, a horizontal shaft arranged between said rollers, T-shaped beetles pivotally mounted on the said horizontal shaft, a pair of flank members, means whereby the flank members are rigidly secured on their respective guide rods at a fixed distance apart, means for slidably supporting the guide rods transversely of the beetles, cams arranged to operate on the inner faces of the flank members, means to rotate said cams, a roller on the lower end of each beetle acted on by the respective flank members so that the oscillation of the beetle is effected during the first half thereof by a positive thrust and in the latter half by gravity.

13. Beetling engines for beetling cloth comprising a pair of rollers for supporting the cloth, a horizontal shaft arranged between said rollers, T-shaped beetles pivotally mounted on the said horizontal shaft, a pair of flank members, means whereby the flank members are rigidly secured on their respective guide rods at a fixed distance apart, means for slidably supporting the guide rods transversely of the beetles, cams arranged to operate on the inner faces of the flank members, means to operate said cams, a roller on the lower end of each beetle acted

on by the respective flank members so that the oscillation of the beetle is effected during the first half thereof by a positive thrust and in the latter half by gravity, a rotatable shaft, means for driving said shaft, a cam member slidable on said shaft and provided with a cam slot, a fixed pin engaging with said cam slot, a geared ring rotatable and slidable with said cam member, a second geared ring fixed on the shaft of each of the cloth rollers and each rotatable and axially movable by the first mentioned geared ring to effect rotation and side to side movement of the cloth rollers, an eye provided on each beetle, a locking bar passing through said eye, means for holding said locking bars against axial movement whilst permitting rotation thereof, and means whereby said bars are turnable independently so as to permit and prevent sliding movement thereon of the eye engaged thereby.

14. Beetling engines for beetling cloth comprising a pair of rollers for supporting the cloth, a horizontal shaft arranged between said rollers, T-shaped beetles pivotally mounted on the said horizontal shaft, a pair of flank members, means whereby the flank members are rigidly secured on their respective guide rods at a fixed distance apart, means for slidably supporting the guide rods transversely of the beetles, cams arranged to operate on the inner faces of the flank members, means to rotate said cams, a roller on the lower end of each beetle acted on by the respective flank members so that the oscillation of the beetle is effected during the first half thereof by a positive thrust and in the latter half by gravity, a rotatable shaft, means for driving said shaft, a cam member slidable on said shaft and provided with a cam slot, a fixed pin engaging with said cam slot, a geared ring rotatable and slidable with said cam member, a second geared ring fixed on the shaft of each of the cloth rollers and each rotatable and axially movable by the first mentioned geared ring to effect rotation and side to side movement of the cloth rollers, stopper members for said beetles, and means for introducing said members to stop the action of any beetle without interfering with the continued action of the beetles remaining or to stop the action of a beetle on one cloth roller only while permitting action of the beetle on the other roller, and reinforcement members adapted to take the thrust on the cloth rollers and due to the impacts of the beetles.

In testimony whereof I affix my signature.

JOHN WILFRED HAUGHTON.
